UNITED STATES PATENT OFFICE.

ALBION KNOWLTON, OF BOSTON, MASSACHUSETTS.

NAILING-MACHINE.

SPECIFICATION forming part of Letters Patent No. 245,077, dated August 2, 1881.

Application filed June 2, 1881. (No model.)

To all whom it may concern:

Be it known that I, ALBION KNOWLTON, of Boston, Suffolk county, State of Massachusetts, have invented certain new and useful Improvements 5 in Nailing-Machines, of which the following is a specification.

My invention relates to that class of machinery for nailing boots and shoes, in which means for feeding a continuous wire and cutting the same into proper nail-lengths are combined with a driver which drives the nails so cut into the boot or shoe, and it has particular reference to the wire-feeding mechanism. I employ for the purpose of feeding the wire feed-rolls which are combined with instrumentalities whereby the rolls have imparted to them an intermittent movement of rotation alternately in opposite directions, the movement in what may be termed the "forward direction" 10 causing the feed of the wire, and the extent of the rearward or return movement determining the length of feed; and I also combine with said rolls means whereby, before the commencement of their return movement, they are separated so as to release their hold on the wire, and after the completion of said return movement are permitted to again come together and close upon the wire. The feed device thus organized possesses, as will be seen, in a general 15 way the characteristics of a four-motion feed. This, of course, is not new, broadly considered, with me, my invention residing in the combination and arrangement of instrumentalities, substantially as hereinafter described, whereby 20 I impart to clamping feed-rolls the said motions.

The nature of my invention, and the manner in which the same is or may be carried into effect, will be understood by reference to the accompanying drawings, in which—

Figure 1 is a perspective view of so much of a boot and shoe nailing-machine as needed to illustrate my improvements. Fig. 2 is a sectional side elevation of the same. Fig. 3 is a 45 front elevation of the same. Fig. 4 is a view of the movable feed-roll and shaft and spring-supporting bracket detached. Fig. 5 is a view of a portion of the main shaft and shoe-feed lever and adjacent cams thereon. Fig. 6 is a 50 view of the sliding cutter-bar detached. Fig. 7 is a side elevation of the upper part of the shoe-feed lever.

Like letters indicate like parts in the several figures.

A is the frame of the machine; B, the main shaft; C, the driver-bar, with its driver D moved in one direction by cam E, and in opposite direction by a spring, which is not shown. F is the shoe-feed lever, which encircles at its upper end an eccentric, a, on shaft B, and moves 55 on a fulcrum adjustable in the slot b for the purpose of regulating the length of feed. The wire passes from a bobbin (not shown) down back of the cam E, through a passage, b', terminating in a fixed steel tube, c, (shown detached on the right of Fig. 3,) under the lower end of which moves the reciprocating cutter-bar G, operated to move in one direction by means of cutter-bar lever H and cam I on shaft B, and in the other direction by means of spring J. 60 The parts thus far described are combined and arranged to operate as usual in machines of 65 this class, and require no further description here.

The wire-feeding instrumentality consists of 70 two rolls, d e, having their contiguous faces grooved, or otherwise formed, to receive and hold the wire which passes down between them. Roll d is mounted to revolve on a pin fixed to the frame of the machine. Roll e is fixed on a 75 short shaft, f, which is journaled in a spring-supporting bracket, K, fixed to the machine-frame and adapted to permit the roll e and its shaft to move to and from the other roll. The spring-bracket normally holds roll e with clamping-pressure against roll d. The rear end of shaft f is provided with two arms, g h. To the one, g, is attached a spring, i, fixed at the other end of the machine-frame. The spring is under tension, and tends to rotate the shaft in one 80 direction, the extent of movement in this direction being determined by the thumb-screw j, which screws through a bracket on the frame and has its upper end under the arm g, this upper end being surmounted by a cushion, j', 85 of wood or other sound-deadening material. The other arm, h, is a wiper-arm, which is acted on by cam k on shaft B. By the action of this cam upon the arm the feed-roll shaft is rotated in a direction opposite to that in which it is 90 moved by the spring i.

Upon the hub of the shoe-feeding lever which encircles the eccentric a on shaft B is an enlargement or projection, l, which, during the

oscillation of the shoe-feeding lever, bears at proper intervals against the lower end of the spring-supporting bracket K, and presses this bracket outward, so as to separate the feed-roll e from the feed-roll d to such an extent as to cause the rolls to release their hold upon the wire. The two rolls d and e are provided with segment gears, as shown, so that the movement of the roll d may be imparted to the roll e, the gear-teeth being of such length as to permit the feed-rolls to move apart the requisite distance without throwing the teeth out of gear.

The parts are so timed to move relatively to one another that at the proper moment the cam k will act on the wiper-arm h to rock the feed-shaft f in the direction requisite for the feed of the wire. This movement will be imparted to the feed-rolls, which at this time are closed upon the wire, and they will consequently feed down the wire a predetermined distance, the lower end of the wire passing from the steel tube e into a corresponding opening in the cutter-bar beneath, where it is operated on and disposed of in the usual way. The cam is of such length as to hold the rolls in this position until, during the oscillatory movement of the shoe-feeding lever, the projection l comes opposite to and bears against the spring-bracket K to such an extent as to separate the feed-rolls. At this instant the arm h is released from control of its cam, and the spring i at once acts to partially rotate the shaft in the opposite direction, returning the shaft and the feed-rolls to the position from which they started, the extent of this rearward or return movement being determined by the position of the adjustable or regulating thumb-screw j. As soon as the parts are returned to this position the projection l ceases to act on the spring-bracket, and the feed-rolls once more close upon the wire to again feed it forward at the proper time, as above described.

It will thus be seen that I obtain a wire-feed device consisting of clamping feed-rolls geared together so as to be positively driven in unison, and having at definite intervals movement to and from one another for the purpose of grasping and releasing the wire, and movement of partial rotation alternately in opposite directions for the purpose of feeding the wire forward a predetermined distance, and returning

to the position from which they started in order to take a fresh hold on the wire; and the organization of parts by which these various movements are imparted to said rolls is such as to combine strength and efficiency with simplicity, compactness, and economy.

Having described my invention, and the manner in which the same is or may be carried into effect, what I claim, and desire to secure by Letters Patent, is—

1. In a nailing-machine for boots and shoes, wire-feed rolls geared together so as to move in unison, in combination with actuating mechanism, substantially as described, whereby the said rolls are caused to move to and from one another and to rotate on their axes alternately in opposite directions at the times and in the manner substantially as specified.

2. The feed-rolls geared together so as to move in unison, in combination with the feed-shaft carrying one of said rolls, the shaft-supporting bracket, the two arms fixed to said shaft, the spring i, and the cam k, arranged and operating substantially as hereinbefore set forth.

3. The combination, substantially as hereinbefore set forth, of the feed-roll d, the feed-roll e, geared thereto, the feed-shaft f, the arms g h, the cam k, the spring i, and the adjustable regulating-screw j.

4. The feed-roll shaft f and spring-bracket K, in combination with the oscillatory shoe-feeding lever, and enlargement or projection l thereon, substantially as and for the purposes set forth.

5. The feed-rolls geared together and mounted one on the machine-frame and the other on a rotatable shaft provided with drivers, as described, in combination with the shaft-supporting spring-bracket, the oscillating shoe-feeding lever and enlargement thereon, the spring and the rotating cam for giving movement to said shaft, and the adjustable regulating-screw, the combination being and acting substantially as hereinbefore set forth.

In testimony whereof I have hereunto set my hand this 1st day of June, A. D. 1881.

ALBION KNOWLTON.
